UNITED STATES PATENT OFFICE.

CHRISTIAN A. SCHMIDT, OF HOBOKEN, NEW JERSEY.

DESIGN FOR A PENDANT.

SPECIFICATION forming part of Design No. 16,752, dated June 22, 1886.

Application filed January 30, 1886. Serial No. 190,374. Term of patent 7 years.

To all whom it may concern:

Be it known that I, CHRISTIAN A. SCHMIDT, a citizen of Russia, and a resident of Hoboken, in the county of Hudson and State of New Jersey, have invented a new and original Design 5 for a Chenille Pendant, of which the following is a full, clear, and exact description, reference being had to the accompanying drawing, making part of this specification, and in which a to face of my newly-designed pendant is shown.

The leading feature of my design consists in the body having its lower end forked, and in pendent ornaments on the ends of the shanks of the forked part.

15 The drawing shows a face view of my newly-designed pendant.

A is the body of the pendant.

B are two shanks at the lower end of the body.

20 C are pendent ornaments of the nature of a tassel on the lower ends of the shanks B.

D is a tuft at the lower end of the body and at the upper ends of the shanks.

25 E are loops projecting downward from the tuft D over the shanks.

F is a tuft at the upper end of the body.

G is a hanging loop at the upper end of the body.

Having thus described my design, I claim as new and desire to secure by Letters Patent— 30

1. The design for a pendant herein shown and described, the same consisting of the body A, the shanks B, the tufts D and F, the loops E, and the pendent ornaments on the ends of the shanks. 35

2. The design for a pendant herein shown and described, the same consisting of the body A, the shanks B at the lower end of the same, pendent ornaments on the ends of the shanks B, and the loops E, extending over the shanks. 40

In testimony that I claim the foregoing as my invention I have signed it this 27th day of January, 1886.

CHRISTIAN A. SCHMIDT.
